UNITED STATES PATENT OFFICE

129,499

DESIGN FOR A NECKTIE RACK

Arthur Waterman, Philadelphia, Pa.

Application December 24, 1940, Serial No. 97,595

Term of patent 7 years

To all whom it may concern:

Be it known that I, Arthur Waterman, a citizen of the United States and resident of the city and county of Philadelphia, in the State of Pennsylvania, have invented a new, original, and ornamental Design for a Necktie Rack, of which the following is a specification, reference being had to the accompanying drawing forming a part thereof.

In the drawing:

I claim:

The ornamental design for a necktie rack, as shown.

ARTHUR WATERMAN.
